UNITED STATES PATENT OFFICE.

CHARLES S. JENKINS, OF LANSDALE, PENNSYLVANIA.

PLOW.

SPECIFICATION forming part of Letters Patent No. 243,138, dated June 21, 1881.

Application filed April 9, 1881. (No model.)

To all whom it may concern:

Be it known that I, CHARLES S. JENKINS, of Lansdale, in the county of Montgomery and State of Pennsylvania, have invented an Improvement in Plows, of which the following is a specification.

My invention has reference to plows; and it consists in pivoting the colter loosely to the plowshare or the frame of the plow; further, in securing to the side of the colter a guide-wheel which is adapted to adjustment; further, in combining the guide-wheel with a scraper to clean the same; and, finally, in providing means to secure the colter rigidly in any desired position, all of which is more fully set forth in the following specification, and shown in the accompanying drawings, which form part thereof.

In the drawings, Figure 1 is a perspective view of a plow embodying in it my invention. Fig. 2 is a side elevation of same. Fig. 3 is a view of the axle and its means of being secured to the colter, frame, or pivoted arm. Figs. 4 to 9, inclusive, show diagrams illustrating certain features in the old and new manner of plowing.

Heretofore plows have been made with rigid knife, wheel, or plow colters, or with a spring-arm, and the guide-wheel located some distance in advance of the colter. To keep the colter cutting uniformly in plows of the old construction it is necessary to make the plowshare change its level continuously by means of the front guide-wheel secured to the frame, as shown at *x* in Fig. 4, in which the cut of the plowshare is nearly always parallel to the surface and always about six inches below it.

In my improved plow the guide-wheel is attached to the colter, and, being pivoted to the plowshare or the frame, it allows the colter to automatically follow the variations in the level of the ground, and allows the plowshare to turn the ground irregularly or on a practically uniform level and in a straight line, as shown at *y* of Fig. 4.

The latest improved plows in common use are made with a wheel and colter or sod-scalper, (commonly called a "jointer,") both of which are attached rigidly to the beam, the cutter being located some distance in advance of the plowshare and the wheel at or near the end of the beam.

In many of the plows of the present day objectionable features are found, and which I have endeavored to overcome. Some of these features may be considered the following: Generally they are too top-heavy and cannot be conveniently handled in the field, and by locating the wheel at the front end of the pole and near the horses the single-trees or traces are liable to catch in short turning.

Stones are liable to wedge in between the colter and plow and throw it out of the ground or to stop the team. The rigid wheel will not admit the plow to enter the ground to its proper depth, nor the colter to enter at all, till the plow has moved a considerable distance.

The colter (sod-scalper) is usually set to run about two inches in depth, and the plow (by the adjustable wheel on the beam) to run about four inches deeper. This arrangement on level ground will turn a uniform furrow of six inches in depth, as shown at *x*, Figs. 4 and 5, which cannot be varied at the will of the plowman to suit deep or shallow soil, as shown, and which is found in different parts of the same field, and even in the same furrow.

In order to keep the nose of the colter at all times, if possible, below the sod, the nose of the plow is turned downward, thus causing unnecessary inclination to dip, unnecessary pressure upon the wheel, and consequently unnecessary labor for the team.

When the wheel is upon a slight elevation of ground and the colter is over a slight depression, as shown in Fig. 7, it (the colter) will be entirely out of the ground, and when the wheel is in a slight depression and the colter in an elevation, it will run too deep and not turn the grass under.

In doubling together, the first two furrows should be plowed shallow, the next two a little deeper, and the next two still deeper, and so on; otherwise there will be a high ridge where the first two furrows are turned together on top of the undisturbed surface beneath them. With the plow in common use none of these variations can be made without frequent adjustment of the wheel and cutter by means of an iron wrench.

In turning furrows left and right, when it comes to the last furrow the wheel cannot be kept upon it, and the plow, having an undue inclination to dip, for purposes above stated,

will, in spite of the plowman, run into the ground to the beam.

In breaking up a sod and plowing parallel with old open furrows the plow will run some 5 six inches deeper than the old furrow, turning up sometimes five or six inches of the clay subsoil, as shown in Fig. 6, which should never be done at one plowing.

In my improved plow all these imperfections 10 are overcome by attaching the wheel which regulates the depth of the sod-scalper to the colter and pivoting the latter to the plow or plow-frame. By this arrangement the colter is free to automatically follow the variations in 15 the level of the ground, cutting its two inches, and no more, in low as well as in high places, leaving the plow to run independently of it and subject to its natural inclination or to the will of the plowman, in which case no subsoil need 20 ever be turned, as shown in Figs. 8 and 9.

A is the plow-frame, and B is the ordinary plowshare. To the plow share or frame at C is pivoted an arm, D, which extends in front of the plowshare and carries firmly secured to it 25 a colter, E, for cutting and turning the sod. There are several pivot-holes, C, for adjusting the pivot of the arm D. This arm D is guided vertically between two bars, F, secured between the frame and plowshare, said bars being provided with a series of holes, G, which register 30 with a hole, H, on arm D, which is adapted to be adjusted rigidly at any height by means of same and a pin, I. To the side of the colter or the arm D, and secured in slot J, is a bracket, 35 K, carrying a pin or axle, L, upon which the colter guide-wheel M is located and secured. The scraper N is secured to the arm D back of the wheel M, both of which may be adjusted vertically or laterally to and from each other.

40 The operation is as follows: The plow being dragged through the ground, the plowshare may always be drawn on a practically level line, as shown at y, Fig. 4, or may be varied at will by the driver, as shown in Fig. 9; and if 45 there are any variations in the surface of the ground the colter guide-wheel M causes the colter to rise or fall so that it shall always cut about two inches in depth. The wheel M makes the colter self-adjusting and self-governing.

50 Any grass, dirt, &c., which may be carried up on the wheel is cleaned off by the scraper N, and grass which might become pressed in between the front of the colter and wheel, and

tend to bind about its bearing, is immediately carried down and discharged, and thus the 55 colter and wheel is self-cleaning.

If it is not desired that the colter should cut two inches in depth, the wheel M may be adjusted lower by means of bracket K; and if the use of the colter is not desired, it can be raised 60 up and kept above the ground by means of the guide-bars F and pin I, as indicated in dotted lines, Fig. 2.

I am aware of the patent to Lyons, dated October 19, 1875, but claim nothing therein 65 shown or described.

Having now described my invention, what I claim as new, and desire to secure by Letters Patent, is—

1. In a plow, a colter pivoted to the plow 70 and adapted to rise and fall by its own gravity independently of the plow, to accord with the undulations of the ground, as and for the purpose specified.

2. In a plow, a colter secured to an arm pivoted to the plow, said colter being adapted to rise and fall by its own gravity independently of the plow, to accord with the undulations of the ground, substantially as and for the purpose specified. 75

3. In a plow, a colter pivoted to the plow, in combination with a wheel secured to said colter, to cause the same to rise and fall in accordance with the undulations or variations in the surface of the ground, as and for the purpose specified. 80

4. In a plow, the combination of the plow-frame A, plowshare B, pivoted arm D, colter E, guide-wheel M, and scraper N, as and for the purpose specified. 90

5. In a plow, the combination of the pivoted colter E and its arm, slot J, adjustable bracket K, wheel M, and scraper N, as and for the purpose specified.

6. In a plow, a colter, E, in combination with 95 a guide-wheel, M, pivoted to the same, and mechanism to adjust said wheel with reference to the colter, substantially as and for the purpose specified.

In testimony of which invention I hereunto 100 set my hand.
